SANFORD S. VAUGHAN AND LEMUEL M. BUSHNELL, OF CHICAGO, ILLINOIS,
ASSIGNORS TO THE VAUGHAN & BUSHNELL MANUFACTURING COMPANY,
OF SAME PLACE.

DESIGN FOR A WRENCH.

SPECIFICATION forming part of Design No. 29,108, dated July 26, 1898.

Application filed December 6, 1897. Serial No. 660,979. Term of patent 14 years.

To all whom it may concern:

Be it known that we, SANFORD S. VAUGHAN and LEMUEL M. BUSHNELL, citizens of the United States, residing at Chicago, Cook county, Illinois, have invented and produced a new and original Design for Wrenches, of which the following is a specification.

In the accompanying drawings, Figure 1 is an elevation of a wrench embodying my design; Fig. 2, a cross-sectional view taken on line *x x* of Fig. 1, and Fig. 3 a cross-sectional view taken on line *y y* of Fig. 1.

A is the wrench proper; B, openings or recesses in the handle; C, ribs along the outer edges of the handle and inner edges of the jaws, and D depressed portions inside of the ribs of the handle and outside the ribs of the jaws.

The leading feature of our design consists in a handle portion having jaws at one end and continuous ribs along the outer edges of the handle, with depressed portions inside thereof and along the inner edges of the jaws and with depressed portions outside thereof, the whole presenting an ornate and attractive appearance, as shown in the drawings.

We claim—

The design for a wrench herein shown and described.

SANFORD S. VAUGHAN.
LEMUEL M. BUSHNELL.
